United States Patent Office

Des. 213,710
Patented Apr. 1, 1969

213,710

HELICOPTER TOY

Peter Charles Jacobs, Edmonton, Alberta, Canada, assignor to Jaycopter Corporation Ltd., a corporation of Canada

Filed Apr. 8, 1968, Ser. No. 11,361

Claims priority, application Canada Dec. 7, 1967

Term of patent 14 years

Int. Cl. D21—02

U.S. Cl. D34—15

Fig. 1.

Fig. 2.

Fig. 3.

FIGURE 1 is a top plan view thereof;
FIGURE 2 is a front elevation showing my helicopter toy;

FIGURE 3 is a bottom plan view;
FIGURE 4 is a rear elevation; and
FIGURE 5 is a right side elevation.
The left side elevation is substantially a mirror image of the right side elevation.

I claim:

The ornamental design for a helicopter toy, as shown and described.
